UNITED STATES PATENT OFFICE.

BIRGER OSLAND, OF CHICAGO, ILLINOIS.

BILGED METALLIC PACKAGE.

1,006,780.

Specification of Letters Patent. Patented Oct. 24, 1911.

Application filed September 3, 1910. Serial No. 580,442.

To all whom it may concern:

Be it known that I, BIRGER OSLAND, a citizen of the United States, and a resident of Chicago, in the county of Cook and State of Illinois, have invented a certain new and useful Bilged Metallic Package; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to metallic packages, and particularly to the construction of bilged sheet-metal barrels. In the manufacture of packages of this class, it has been customary to longitudinally rib the same, and in order to take up enough metal to give the barrels the proper bilge, the ribs have been gradually narrowed from their ends inwardly, thus producing the weakest point at the middle of the package.

25 The object of my invention is to overcome the objection incident to the old construction of bilged barrels of the class described, by so forming and arranging the reinforcing ribs as to make the package body of substantially equal strength throughout its length and at the same time impart a bilge formation thereto.

The invention is fully described in the following specification, and while, in its broader aspect, it is susceptible of embodiment in numerous forms, a preferred embodiment thereof is illustrated in the accompanying drawings, in which,—

Figure 1 is a central longitudinal section 40 of a barrel body embodying my invention. Fig. 2 is a central cross-section thereof on the line 2-2 in Fig. 1. Fig. 3 is an end view of the barrel body. Fig. 4 is a cross-section on the line 4-4 in Fig. 1. Fig. 5 is a developed view of a portion of the barrel body, and Fig. 6 is an enlarged longitudinal section of an end portion thereof with an end closure secured thereto.

Referring to the drawings, 10 designates a sheet-metal barrel body, which has transversely spaced portions preferably drawn inwardly at the ends thereof and closely compressed to provide the longitudinally extending end reinforcing ribs 11, and has similarly spaced inwardly drawn closely compressed portions at the middle thereof

and preferably extending to adjacent the ends of the body to provide the middle reinforcing ribs 12.

The ribs 11 at opposite ends of the body are arranged to longitudinally register with each other, and the ribs 12 preferably alternate therewith around the body, as shown. The end ribs 11 are of greatest depth at their outer ends and gradually diminish toward the center of the package, preferably dying out or losing themselves in the package body slightly short of its center.

The middle reinforcing ribs 12 are of greatest depth at the center of the package and gradually diminish outwardly preferably from points which approximately register transversely with the inner ends of the ribs 11 until they lose themselves in the body adjacent its ends. The ribs are of suitable depth and preferably diminish at their ends in such proportion relative to the ribs 11 as to make the barrel body of approximately equal strength throughout its length. The end ribs 11, in addition to reinforcing the body are also of suitable depth and sufficiently tapered to give the body the proper bilge.

The ribs 11 and 12 at the ends of the package body are rolled flat against the body to form the customary closure receiving portions or chimes at such ends. If it is desired to double-seam the outer edge of a closure with the body edge, as shown at 13, the outer ends of the ribs 12 may be cut away to provide a flange 14 for interlocking with the closure edge. The chime is shown in the present instance as being reinforced by a band 15.

It is evident that I have provided a bilged sheet metal package, which, instead of being of minimum strength at its central portion is, if anything, of greatest strength at such portion, as the middle ribs slanting off to both sides and being deepest in the middle act as complete trusses in resisting any pressure from without. Furthermore the end ribs, running only one way serve to give the package the proper bilge shape, and also the necessary strength at the package ends, instead of these ribs producing a complete truss construction they form two halves of a truss pulling in opposite directions which, when taken alone, produce a package of weak central construction, but when combined with central ribs running in the same direction co-operate therewith to produce a

package of very great strength at its central portion, where strength is most desired. It is also evident that my construction of bilged package enables manufacturers to use 5 very much lighter metal in its construction than is possible with any other metallic package of its nature on the market, due to the peculiar arrangement of ribs which impart great resisting strength to the package.

10 I wish it understood that my invention is not limited to any specific construction or arrangement of the parts except in so far as such limitations are specified in the claims.

Having thus described my invention, what 15 I claim as new and desire to secure by Letters Patent, is,—

20 1. A bilged metallic package, having alternating sets of central and end ribs; all running longitudinally of the package with both ends of the central ribs extending between the inner ends of the contiguous end sets of ribs to coöperate therewith to strengthen the package throughout its length.

25 2. A bilged metallic package, having central and opposite end sets of closely compressed ribs, with both ends of the central ribs lapping the contiguous ends of the end ribs.

30 3. A bilged metallic package having longitudinally-extending and bilging ribs in each end portion thereof, and center reinforcing ribs alternating with at least a portion of the end ribs and extending out- 35 wardly at their ends beyond the inner ends of the end ribs.

4. A bilged metallic package having end bilging and reinforcing ribs gradually diminishing in depth to their inner ends, and center reinforcing ribs which have their ends extending outwardly beyond the inner ends of the end ribs and gradually diminishing in depth.

5. A bilged metallic barrel having its body comprising a single piece and provided at its ends with longitudinally-extending bilging and reinforcing ribs, which terminate at their inner ends adjacent the barrel center, and provided at its central portion with longitudinally-extending ribs, which are of greatest depth at the barrel center and have their ends extending between the associated end ribs and gradually diminishing in depth.

6. A bilged sheet-metal barrel body having end bilging and reinforcing ribs and center reinforcing ribs extending longitudinally thereof, the end and center ribs alternating, with the end ribs diminishing in depth toward their inner ends and losing themselves in the body adjacent its center and the center ribs diminishing in depth from their centers outwardly and losing themselves in the body adjacent its ends.

In testimony whereof, I have hereunto signed my name to this specification in the presence of two subscribing witnesses:

BIRGER OSLAND.
